UNIFORM

Roy A. Merrick, Minneapolis, Minn., assignor to
 Shane Uniform Company, Inc., Evansville,
 Ind., a corporation of Indiana

Application July 24, 1940, Serial No. 347,290

2 Claims. (Cl. 2—74)

My invention relates broadly to garments and more particularly to an improved pattern and construction of uniform for women.

One of the objects of my invention is to provide a pattern and construction of uniform for women which is formed of separable coacting portions which may be independently and readily laundered.

Another object of my invention is to provide a construction of two part uniform readily adaptable to various proportions of the bust measure, waist measure and hip measure.

Still another object of my invention is to provide a construction of two part uniform comprising an underbody provided with tape ties and a reversible front panel adapted to be removably secured to the underbody by means of buttons and belt member.

A further object of my invention is to provide a two part uniform comprising an underbody and a reversible front portion including an apron of double thickness adapted to present a fresh external surface for the uniform in either of its connected positions with respect to the underbody.

A still further object of my invention is to provide a pattern for a two part garment which includes a coat portion and a front panel portion where the front panel portion is connectible to the coat portion through adjustably positioned and removable buttons with a belt contiguous with the panel portion adapted to embrace the coat portion and to be adjustably secured with respect thereto through adjustable and removable buttons.

Another object of my invention is to provide a construction of two part uniform including an apron portion provided with a pocket individual to opposite sides of the apron portion and adapted to present a fresh wearable surface for the uniform when the apron is secured in either of two positions with respect to an underbody or coat portion of the garment.

Other and further objects of my invention reside in the pattern and construction of garment as set forth more fully in the specification hereinafter following by reference to the accompanying drawings, in which:

Figure 1 is a front view of the assembled garment showing the front panel in buttoned relation to the underbody or coat portion of the garment; Fig. 2 is a back view of the assembled garment illustrated in Fig. 1; Fig. 3 is a front elevational view of the underbody or coat portion of the garment shown in assembled position

before attachment of the front panel portion of the garment; Fig. 4 is a front view of the removable and reversible front panel portion of the garment; Fig. 5 is a fragmentary view of one of the detachable and adjustable buttons employed on the underbody portion of the garment for detachably securing the front panel portion of the garment; Fig. 6 is a rear view of the adjustable securing means for one of the removable buttons carried by the underbody or coat portion of the garment; Fig. 7 is a fragmentary longitudinal sectional view taken on line 7—7 of Fig. 6; Fig. 8 is a transverse sectional view taken through the underbody or coat portion of the garment on line 8—8 of Fig. 3; Fig. 9 is a transverse sectional view on a somewhat enlarged scale taken on line 9—9 of Fig. 1 and illustrating the assembled relationship of the reversible front panel portion of the garment with respect to the underbody or coat portion of the garment; Fig. 10 is a vertical sectional view taken through the front panel and apron portion of the garment and illustrating a portion of the front panel and apron portion in perspective; Fig. 11 is a fragmentary perspective view of the adjustable belt employed for securing the apron portion with respect to the underbody or coat portion of the garment; Fig. 12 is a perspective view of the reverse side of the belt illustrated in Fig. 11 and showing more particularly the adjustable means employed for controlling the effective length of the belt with respect to the underbody or coat portion of the garment; and Fig. 13 is a vertical sectional view taken on line 13—13 of Fig. 12 showing the coacting portions of the securing belt in secured position.

Referring to the drawings in detail, reference character 1 designates the underbody or coat portion of the garment which is shaped to conform to various proportions of the bust measure, waist measure and hip measure. The coat portion terminates at the front in relatively widely separated marginal portions 2 and 3 which are adapted to be drawn together by means of tape ties 4 and 5 respectively. The sets of tape ties are adapted to be tied in suitable bows indicated at 6. The underbody includes a collar portion 7 and sleeve portions 8 and 9. The sleeve portions 8 and 9 may be provided with suitable flexible cuff links 8a and 9a. Adjacent the collar portion 7 and near the upper extremities of the marginal edge portions 2 and 3 there are provided reenforcing strips 10a and 11a on the inside of the material of the underbody serving as reenforcing means for the passage of the securing

means of the detachable buttons 10 and 11 respectively. Immediately adjacent the collar portion 7 and the extremities of the marginal edge portions 2 and 3, I provide buttons 23 and 24 which serve as securing means for the detachable front panel 15.

As shown in Fig. 4 the front panel 15 includes a neck portion having lapels 12 and 14 which substantially cover buttons 10, 23, 11 and 24, when the neck portion is attached to the underbody of the coat portion. The front panel is provided with button holes at 10' and 23' and at 11' and 24' for receiving buttons 10, 23, 11 and 24 respectively.

The underbody or coat portion 1 is provided intermediate the collar portion and the waist line with reenforcing strips 25 and 26 on the inside of the material constituting the underbody or coat portion of the garment. These strips 25 and 26 serve as reenforcing means for detachably securing the buttons 20 and 21 in different spacial positions. As indicated in Figs. 5, 6 and 7, the buttons 20 and 21 are each detachably and may be secured through selected spaced eyelets provided at 20a, 20b, 20c and 21a, 21b and 21c as shown, thereby affording variously spaced lateral supporting positions for the front panel 15. Buttonholes 20' and 21' are provided in the panel 15 to engage the adjustably spaced buttons 20 and 21 in the underbody or coat portion of the garment.

It will be observed that the front panel 15 is formed from two layers of fabric indicated at 15a and 15b in Fig. 10. These layers of fabric are stitched at their marginal edges and connect with the independent lapels 12 and 14 at the upper extremity and are stitched at 15c to the belt 16 at its lower extremity. The belt 16 extends transversely with respect to the front panel 15 and includes projecting portions 16a and 16b. The projecting portion 16a carries a multiplicity of groups of buttonholes which I have indicated at 23a, 23b, 23c, 23d and 24a, 24b, 24c and 24d. These groups of buttonholes are adapted to receive detachable buttons 23 and 24. The buttons 23 and 24 may be attached in selected holes in order to conform the uniform to various body sizes. The portion of the belt 16b carries buttonholes 23' and 24' adapted to engage buttons 23 and 24 respectively, when the parts of the belt are interconnected at the rear of the uniform shown in Fig. 2.

The skirt portion is indicated at 17 connected at its upper extremity with belt 16 by stitches along the line 17c. The skirt 17 is formed from a double thickness of fabric indicated at 17a and 17b, which fabric is doubled upon itself to provide two independent wearing surfaces. Each wearing surface includes a pocket. Pocket 18 is fastened to the surface 17a while pocket 19 is fastened to the surface 17b. Accordingly, a pocket is provided in the skirt portion 17 whether the skirt be worn either normally or in the reverse position.

The fastening means have been shown as removable buttons which add to the ornamental character of the uniform. It will be understood, however, that snap fasteners may be employed or other forms of detachable connectors provided which will permit quick attachment, detachment or reattachment of the front cover portion with respect to the coat portion. When the surface of the front cover portion 15 or skirt 17 becomes soiled the front cover portion may be readily de-

tached from the coat portion, raising the lapels 12 and 14 to permit more ready access to the substantially concealed fastening means beneath the lapels 12 and 14. The lapels 12 and 14 are each reversible in position as the front cover portion is reversed. The entire front cover portion is reversed and reattached to the coat portion, the lapels 12 and 14 being moved to a position coacting with the collar portion 7 of the coat portion. It is necessary to remove the buttons 23 and 24 and reinsert these buttons in reverse position in order to secure the front cover portion in reversed position with respect to the coat portion.

15 The coat portion and the front cover portion are each separately launderable and thus reduce laundry costs in that each portion after washing and drying may be opened out flat and pressed in a flat-work ironer.

20 While I have disclosed my invention in certain preferred embodiments, I realize that modifications may be made and I intend no limitations upon my invention other than may be imposed by the scope of the appended claims.

25 What I claim as new and desire to secure by Letters Patent of the United States is as follows:

1. A garment comprising a pair of coacting separately launderable portions, one of said portions constituting a coat having spaced marginal co-extensive front edge portions and a collar member, means interconnecting said marginal coextensive front edge portions, fastening means carried by the front of said coat, the other of said 30 separately launderable portions constituting a reversible front cover member extending across the gap between the marginal edge portions of said coat, reversible lapels carried by the upper periphery of said reversible front cover member and conforming with the collar member on said coat, and means carried by said front cover member detachably engageable with the fastening means carried by the front of said coat, the reversible lapels on said front cover member operating to partially conceal certain of said fastening means in either the normal or reversed position of said front cover member.

2. A garment comprising a pair of coacting separately launderable portions, one of said portions constituting a coat having spaced marginal co-extensive front edge portions and a collar member, means interconnecting said marginal coextensive front edge portions, fastening means carried by the front of said coat, the other of said 50 separately launderable portions constituting a reversible front cover member extending across the gap between the marginal edge portions of said coat, independent reversible lapels carried by the upper periphery of said reversible front cover member and conforming with the collar member on said coat, coacting fastening means carried by said front cover member for detachably engaging the fastening means carried by the front of said coat, and an adjustable transversely extending belt connected with said front cover member for maintaining said front cover member in position, said independent reversible lapels on said front cover member operating in either 55 normal or reverse position of said front cover member to substantially conceal certain of the fastening means on said coat and on said front cover member.

ROY A. MERRICK.
